DESCRIPTION

FIG. 1 is a first perspective view of an electric actuator for medical device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a second perspective view showing the electric actuator for medical device.

The broken lines shown in the figures are for the purpose of illustrating portions of the electric actuator for medical device and form no part of the claimed design.
